UNITED STATES PATENT OFFICE.

HARRY A. LUTTON, OF JERSEY CITY, NEW JERSEY.

COMBINATION SUPPORTING FRAME AND GUTTER.

Application filed February 7, 1927. Serial No. 166,508.

This invention relates to greenhouse structures and has particular reference to a combined support for the glass or transparent panels and a condensation drain gutter for receiving and carrying off the condensation which collects on the under faces of the glass or transparent panels.

One of the principal and outstanding objects of the present invention is to provide a combined support and gutter which in addition to adding to the rigidity of the support of the transparent panels of the greenhouse, affords drain gutters for the condensation, which gutters are of all metal construction and capable of being painted or otherwise coated to prevent rusting and to eliminate contact or rotting of any of the wooden elements of the structure.

Other objects reside in the simplicity of construction, the economy with which the same may be produced and erected, and the general efficiency derived therefrom.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings:—

Figure 1 is a fragmentary vertical sectional view through a greenhouse including a combined panel support and condensation drain gutter constructed in accordance with the invention;

Fig. 2 is a transverse sectional view approximately on the line 2—2 of Fig. 1.

Referring to the drawings by characters of reference, 10 designates the foundation wall, which may be of cement, brick, or any other suitable construction, and upon which a suitable sill 11 is mounted. The rafters 12 are carried by the sill and are connected thereto by brackets 13. The glass or other transparent panels 14 are supported by the combined supporting frame and condensation drain gutter elements constituting the present invention, certain of which elements are in turn supported by the rafters 12 and the remainder of which are disposed between the rafters. These elements or members include substantially U-shaped bars 15, prefer-

ably of metal, and an angle bar 16 also preferably of metal and within the re-entrant angle of which the bight 17 of the bar 15 is seated, suitable fastening means, such as a screw 18, being provided, which passes through the medial portion of the bight and threadedly anchored in the apex of the angle bar. Filler elements 19, preferably in the nature of wooden bars, are mounted within the channel formed by the U-shaped bars 15 and are secured therein by fastening elements, such as screws 20. The filler elements project above the upper open end of the U-shaped bars 15 and have their opposite sides rabbetted as at 21, to afford a seat for the reception of the side edges of the panels 14. Putty 22 and glazing tacks 23 are used in the ordinary manner for attaching and weather-sealing the panels to the filler elements.

The angle bars 16 are of a sufficient size to dispose the ends of their flanges an appropriate distance beyond the bights 17 of the U-shaped bars to form condensation drain gutters 24 between said ends and the U-shaped bars. In view of the fact that the panels 14 are of arcuate shape, the concaved under side of the panels causes the condensation to follow the under surface until it reaches the points of connection with the supports, where it will gravitate into the drain gutters 24, from whence it will be conveyed on to the sill 11 and thence along the inner side of the foundation wall 10. The combined supports and gutters which are supported by the rafters 12 have interposed therebetween, substantially M-shaped capping strips 25 which are mounted on the rafters and suitable clamping elements 26 embrace the angle bars.

From the foregoing it will thus be seen that by combining the angle bars and U-shaped bars in the manner described and illustrated, an extremely strong and rigid support for the glass or transparent panels has been devised which elements combine to define efficient drain gutters for the condensation.

What is claimed is:

1. A combined transparent panel support and condensation drain gutter for greenhouses, comprising frame members respectively consisting of a metal U-shaped bar, a wooden bar within the channel faces thereof to which the transparent panels are attached, and an angle iron within the re-

- entrant angle of which the bight of the **U**-shaped bar is seated to define between said **U**-shaped bar and the angle bar, condensation drain gutters. 35
- 5 2. In a greenhouse structure, a combined transparent panel support and condensation drain gutter including a **V**-shaped bar and a **U**-shaped bar having its bight seated within the **V**-shaped bar, the said **V**-shaped bar having the ends of its divergent flanges protruding laterally beyond the **U**-shaped bar to define together with said **U**-shaped bar, condensation drain gutters on opposite sides thereof. 40
- 10 3. In a greenhouse structure, a combined transparent panel support and condensation drain gutter including a **V**-shaped bar and a **U**-shaped bar having its bight seated within the **V**-shaped bar, the said **V**-shaped bar having the ends of its divergent flanges protruding laterally beyond the **U**-shaped bar to define together with said **U**-shaped bar, condensation drain gutters on opposite sides thereof. 45
- 15 4. In a greenhouse structure, a combined transparent panel support and condensation drain gutter including a **V**-shaped bar and a **U**-shaped bar having its bight seated within the **V**-shaped bar, the said **V**-shaped bar having the ends of its divergent flanges protruding laterally beyond the **U**-shaped bar to define together with said **U**-shaped bar, condensation drain gutters on opposite sides thereof, the **U**-shaped bar having a filler strip within the upper channel portion thereof to which the transparent panels of the greenhouse are attached. 50
- 20 5. In a greenhouse structure, a combined transparent panel support and condensation drain gutter including a **V**-shaped bar and a **U**-shaped bar having its bight seated within the **V**-shaped bar, the said **V**-shaped bar having the ends of its divergent flanges protruding laterally beyond the **U**-shaped bar to define together with said **U**-shaped bar, condensation drain gutters on opposite sides thereof, the **U**-shaped bar having a filler strip within the upper channel portion thereof to which the transparent panels of the greenhouse are attached. 55
- 25 6. In a greenhouse structure, a glazed medium support comprising an element substantially **U**-shaped in cross-section for receiving a retaining means for the glazed medium, and a member underlying the same having upwardly divergent flanges within which the bight of the **U**-shaped element is seated, the free upper ends of the flanges extending beyond the **U**-shaped member and combined with the bight to define together therewith, condensation drain gutters on opposite sides thereof. 60
- 30 4. In a greenhouse structure, a combined transparent panel support and condensation drain gutter including a **V**-shaped bar and a **U**-shaped bar having its bight seated within the **V**-shaped bar, the said **V**-shaped bar having the ends of its divergent flanges protruding laterally beyond the **U**-shaped bar to define together with said **U**-shaped bar, condensation drain gutters on opposite sides thereof. 65
